Leakeage,

UNITED STATES PATENT OFFICE

WILLIAM LEAK, OF CARTHAGE, MISSOURI, ASSIGNOR OF ONE-FOURTH TO WILLIAM V. HATTEN, ONE-EIGHTH TO JAMES M. ENDSLEY, AND ONE-EIGHTH TO JOHN E. ZINN, ALL OF CARTHAGE, MISSOURI

RAIL CLAMP AND BRACE

Application filed November 22, 1927. Serial No. 235,077.

This invention relates to improvements in rail joints and has for an object the provision of means for connecting the meeting ends of adjacent rail sections to hold said ends against vertical movement and thus eliminate rail connecting bars and rail ends, and consequent pounding of said ends.

For this purpose the invention utilizes clamps which engage the outer faces of the connecting bars of the joints and the under faces of the rail sections in a manner to securely hold the bars in contact with the walls of the fishing spaces of the rails.

With the above and other objects in view, the invention further includes the following novel features and details of construction, to be hereinafter more fully described, illustrated in the accompanying drawing and pointed out in the appended claim.

20 In the drawing:—

Figure 1 is a side elevation of a rail joint equipped with the present invention

Figure 2 is a top plan view of the same.

25 Figure 3 is a section on the line 3—3 of Figure 1.

Figure 4 is a view similar to Figure 3 showing a slightly modified form of the invention.

Referring to the drawings in detail where-
30 in like characters of reference denote corre-
sponding parts, the reference character R in-
dicates the meeting ends of adjacent rail sec-
tions which are connected by bars 10. These
35 bars engage the walls of the fishing spaces
upon opposite sides of the rail web 11. They
further engage the under faces 12 of the
heads of the rail, as is usual in the construc-
tion of rail joints.

40 Located centrally upon opposite sides of
the meeting ends of the rail sections are
clamps which contact with the outer faces of
the bars 10. These clamps include plates 13
45 and base portions 14, the latter being connect-
ed to the frame by means of inclined portions

15 which, as shown in Figure 3 of the draw-
ings, engage the upper faces of the base
flanges of the rail. The base portions 14 are
provided with inwardly extending ribs or
flanges 16 which engage beneath the base rails 50
and are provided with openings 17 for the
passage of bolts 18. These bolts extend
through the base portions transversely be-
neath the rails and act in addition to the
usual bolts 19 to securely hold the clamps in 55
position and force the connecting bars 10
against the walls of the fishing spaces. The
upper edges of the bars 10 are provided with
ribs 20 whose outer faces are inclined and
the upper edges of the plates 13 are similarly 60
inclined and bear against these ribs. The up-
per edges of the bars 10 are thus more se-
curely forced against the under faces of the
rail heads.

In Figure 4 of the drawings, the invention 65
is applied to a rail section equipped with
angle bars 21. The clamps are arranged in
the manner shown and described in connec-
tion with Figures 1, 2 and 3, except that the
connecting portions 15' engage the angle bars 70
21 instead of the rail flange. In this form
of the invention, the ribs 20 are omitted.

As shown in Figures 1 and 2 of the draw-
ings, the clamps occupy approximately one-
third of the length of the connecting bars 10 75
or the angle bars 21 and are located centrally
of the length of these bars directly across the
meeting ends of the rail sections. The ends of
the rail sections are thus reinforced and sup-
ported at the point of greatest strain occa-
80 sioned by the passage of wheels across the
joint. The rail ends are thus held against
vertical movement and wear upon the con-
necting bars and consequent pounding and
loosening of the joint is thus prevented. 85

The invention is susceptible of various
changes in its form, proportions and minor
details of construction and the right is herein
reserved to make such changes as properly
fall within the scope of the appended claim. 90

Having described the invention what is claimed is:—

In combination with the meeting ends of adjacent rail sections, bars located within the fishing spaces upon the opposite sides of the rails across said meeting ends, and connecting said ends, clamping plates secured upon opposite sides of the rails in contact with the outer side faces of the bars and extending downwardly and inwardly beneath the base of the rail, bolts extending through the web of the rail and the bars and clamping plates, and bolts extending through the downwardly and inwardly extending portions beneath the rail and connecting the clamping plates.

In testimony whereof I affix my signature.
WILLIAM LEAK.
